CLAIM

The ornamental design for a plate, as shown and described.

DESCRIPTION

FIG. 1 is a top perspective view of a plate of the present disclosure;

FIG. 2 is a bottom perspective view of the plate of FIG. 1;

FIG. 3 is a side view of the plate of FIG. 1;

FIG. 4 is a top view of the plate of FIG. 1; and,

FIG. 5 is a bottom view of the plate of FIG. 1.
